SELECTIVELY FREE WHEELING HUB

James Russell Lloyd, Denver, Colo., assignor to Cutlas
Tool & Mfg. Co., Lyons, Ill., a corporation of Illinois

Application March 10, 1958, Serial No. 49,986

Term of patent 14 years

(Cl. D14—30)

Figure 1 is a perspective view of a selectively free wheeling hub showing my new design. The broken lines are shown for illustrative purposes only.

Fig. 2 is an enlarged face view of the hub with the cam members turned in the opposite direction from that shown in Fig. 1.

The design for the hub disclosed is characterized by the raised rib having the configuration shown.

I claim:

The ornamental design for a selectively free wheeling hub, as shown and described.
